CLAIM

The ornamental design for a portable traction device anchor strap, as shown and described.

DESCRIPTION

FIG. 1 illustrates a top, right perspective view of a portable traction device anchor strap incorporating a new design, the portable traction device shown configured for use without a user associated therewith;

FIG. 2 illustrates a front plan view thereof;

FIG. 3 illustrates a rear plan view thereof;

FIG. 4 illustrates a top elevation view thereof;

FIG. 5 illustrates a bottom elevation view thereof;

FIG. 6 illustrates a right side elevation view thereof; and,

FIG. 7 illustrates a left side elevation view thereof.

In the drawings, the broken lines depict stitching and portions of the portable traction device and form no part of the claimed design.
